UNITED STATES PATENT OFFICE.

ADONIRAM J. COOK, OF WESTERLO, NEW YORK, ASSIGNOR TO THE P & M COMPANY, OF CHICAGO, ILLINOIS, A CORPORATION OF ILLINOIS.

ONE-PIECE SPRING RAIL ANCHOR.

Application filed April 1, 1926, Serial No. 99,160. Renewed December 17, 1926.

The general object of my invention is the provision of a device which when several thereof are combined with track rails and cross ties will prevent the creeping or longitudinal movement of the rails relative to the ties under traffic. Its function is to hold the rail in a fixed position relative to the tie so the force which causes creeping will be transmitted through both the rail and tie to the track ballast.

As is well known by those engaged in railroad operation, the general causes of rail creeping are the wave motion of the track under the alternate application and release of a rolling load; the application of the brake, especially when the wheels slide; curvature of the track when the velocity of the train is greater or less than the velocity for which the outer rail is elevated; and descending grades. Rails creep also excessively on bridges.

The specific object is the provision of a new and improved device of the above general character which shall consist of a single piece 25 of spring metal cut to the required length from a bar of suitable configuration in cross section, and so fashioned that it shall grip the base or flanges of the rail under a high spring tension, thus avoiding the use of bolts 30 or wedges to maintain the same in proper position, and whereby the first cost will be comparatively small.

The invention consists in the new and improved construction and formation hereinafter described and claimed for carrying out the above stated objects, and such other objects as will appear from the following specification.

The accompanying drawing illustrates 40 an example of the anchor constructed according to the best mode of procedure I have so far devised for the purpose, and its application to a track rail and tie.

Figure 1 is a top plan view of parts of a 45 track rail and tie of common construction with my improved anchor in operative position.

Figure 2 is an end elevation view of Figure 1.

Figure 3 is a view in perspective of the 50 spring metal rail anchor as it appears before being applied to the rail.

A piece or section of the required length is cut from a bar of spring metal preferably 55 though not necessarily rectangular in cross

section having opposite plain flat surfaces, as 8 and 9; one end is forged to form a wide upwardly extending flange 11 to engage the edge of one of the rail flanges, and also to form a relatively wide, flat bearing surface 10 for engaging the under surface of the rail flange. However, the end may be fashioned by simply turning up the end of the bar to form a flange 11 of less length, but preferably the flange and flat bearing 60 surface are widened at each side, as shown by 18, dotted line, Figure 3.

The opposite end 14 of the bar is bent downwardly at 19, to provide clearance for the lower edge of the rail base. This end 70 of the anchor is bent upwardly and inwardly, as indicated by the reference numerals 12 and 14, to a position substantially parallel with the body portion at the left of 19.

The end of the portion 14 of the anchor 75 is bent laterally at 15 through an arc of substantially 180° to form a spring tongue 16. The said tongue has a sharp or an angular edge 17 and is bent downwardly, as shown in dotted lines in Fig. 2, so that its lower 80 surface, when the anchor is free of the rail, extends below the lower face of the portion 14 and at an angle greater than the inclination of the said under portion 14.

The anchor thus fashioned is ready to be 85 slipped over the flange 7 of rail 6 to a position adjacent the tie 5, to which the rail is secured by spikes.

Obviously, in driving the anchor onto the flanges of the rail the jaw, comprising the 90 part 14 and the tongue 16, will be bent upwardly, and the tongue 16 will be bent upwardly in a direction to bring its lower surface into alignment with the lower surface of the jaw 14. With this construction, the 95 edge 17 tends to bite into or become imbedded in the top surface of the flange of the rail, and the part 14 is twisted through its longitudinal axis, thereby tending to tilt the anchor about an axis extending transversely 100 of the rail so as to frictionally engage the top surface of the rail flange and so as to urge the jaw 14 and the body portion 9 in a direction to effect a shackle grip on the top and bottom surfaces of the rail base. 105

The spring tension of the distorted metal will thus hold the anchor firmly in proper operative position.

The bending or wave motion of the rail 110 when a train passes over it will not displace

the anchor, but will cause the anchor, by pressing the same against the tie, to more firmly grip the flanges of the rail.

From the foregoing description taken in connection with the drawing it is clear that I have provided a one-piece spring rail anchor which is relatively cheap in first cost, of simple construction, and which will be efficient in operation when applied in connection with a rail and tie.

A plurality of the anchors will normally engage a plurality of ties so that the force or forces which cause creeping of the rail will be transmitted to the several ties at the same time and at different points, thus distributing the energy so the rails and ties will not move relative to the track ballast.

What I claim is:

1. A rail anchor of spring metal fashioned at one end to form a flange, the opposite end bent over through an arc of substantially 180° to a position substantially parallel with the body portion of the anchor, and the extreme end bent sideways through an arc of approximately 180° to form a tongue provided with a sharp edge 17 adapted when the anchor is in position to engage the top surface of a rail flange inside the outer edge of said flange.

2. A rail anchor consisting of a single piece of spring metal having a flat surface, an upwardly extended flange at one end, and a jaw at the opposite end comprising the part 14 and the tongue 16, said tongue being disposed in a plane oblique to the plane of said adjacent part 14 and having a sharp edge adapted to engage the top surface of a rail flange.

3. A rail anchor consisting of a bar of spring metal with a flat surface, one end fashioned to form a flange, the opposite end bent downwardly at 19, the extreme end bent sideways to form a tongue, and the said end including the tongue bent over at 12 to form a jaw, said tongue being disposed in a plane oblique to the flat surface of the bar and having a sharp or angular edge 17.

4. A rail anchor comprising a single piece of metal having some resiliency and formed at one end with a jaw portion for engagement with the top surface of the rail base and formed with a return bend providing a spring tongue, the lower surface of which normally extends obliquely to the lower surface of the jaw, when the anchor is free of the rail and bears with spring pressure against said top surface of said rail base, when the anchor is in its applied position, the said jaw being disposed with relation to the body of the anchor so that the space between the jaw and the body of the anchor is normally insufficient to receive the rail base in operative position therein, whereby

the said jaw is flexed outwardly with relation to the body in application of the device to a rail.

5. A rail anchor comprising a metal bar having some resiliency and formed at one end with a jaw portion for engagement with the top surface of the rail base and formed with a return bend providing a spring tongue, the lower surface of which is normally oblique to the lower surface of the said jaw and is adapted to bear at its extremity against the top surface of the rail base.

6. A rail anchor comprising a metal bar having some resiliency and formed at one end with a jaw portion for engagement with the top surface of the rail base and formed with a return bend providing a spring tongue, the lower surface of which is normally oblique to the lower surface of the said jaw and extends below said lower surface of the said jaw, whereby movement of the anchor transversely of the rail to its applied position, flexes said tongue upwardly and thereby effects a torsional strain on said jaw portion.

7. A rail anchor comprising a metal bar having some resiliency and formed at one end with a jaw portion for engagement with the top surface of the rail base and formed with a spring tongue, the lower surface of which is normally oblique to the lower surface of the said jaw and extends below the lower surface of the said jaw, whereby movement of the anchor transversely of the rail to its applied position, flexes the jaw and the spring tongue outwardly with respect to the body of the anchor, the distortion of the spring tongue being greater than that of the jaw and exerts a torsional strain on said jaw.

8. A one-piece anchor device comprising a spring metal body formed at one end with means for engaging one edge of the rail base and at the other end with a jaw which bears with spring pressure against the top surface of said base and with a return bend providing a spring tongue normally parallel with said jaw when in applied position and presents a cutting edge in opposition to movement of the anchor in a direction to remove it from the rail.

9. A one-piece anchor device comprising a spring metal body formed at one end with means for engaging one edge of the rail base and at the other end with a jaw which bears with spring pressure against the top surface of said base and with a return bend providing a spring tongue, the extremity of which takes a biting hold on the said top surface of the rail base.

In testimony whereof I affix my signature.
ADONIRAM J. COOK.
